[57] **CLAIM**

The ornamental design for a dispensing pump head, as shown and described.

DESCRIPTION

FIG. 1 is a top perspective view of a dispensing pump head showing my new design;

FIG. 2 is another top perspective view showing the side not seen in FIG. 1;

FIG. 3 is a bottom perspective view;

FIG. 4 is a side elevational view;

FIG. 5 is a front elevational view; and

FIG. 6 is a rear elevational view thereof.

The broken lines in FIG. 4 showing a plunger, collar and closure cap are for the purpose of illustrating environmental use only.

Fig. 3.**Fig. 5.****Fig. 6.****Fig. 4.****Fig. 1.****Fig. 2.**
